UNITED STATES PATENT OFFICE.

JOHN A. MURRAY, OF SCRANTON, PENNSYLVANIA.

CAR-COUPING.

SPECIFICATION forming part of Letters Patent No. 339,110, dated March 30, 1886.

Application filed August 27, 1885. Serial No. 175,481. (No model.)

To all whom it may concern:

Be it known that I, JOHN A. MURRAY, a citizen of the United States of America, residing at Scranton, in the county of Lackawanna and State of Pennsylvania, have invented certain new and useful Improvements in Car-Couplings, of which the following is a specification, reference being had therein to the accompanying drawings.

This invention pertains to improvements in car-couplings; and it has for its object, principally, to effect the coupling operation automatically, while it enables the ready uncoupling of the cars, all without requiring the attendant trainman to pass between the cars, which requirement is so frequently the cause of the loss of life or limb or limbs, and to these ends my invention consists of the detailed construction of the parts, substantially as hereinafter set forth, and pointed out in the claims.

In the accompanying drawings, Figure 1 is a longitudinal section of two draw-heads embodying my invention. Fig. 2 is a transverse section, and Fig. 3 is a detached view, of one of the coupling-hooks.

In carrying out my invention I take an ordinary draw-head, A, and form a conical recess or concavity, *a*, in its enlarged flared end; also extending therefrom rearwardly a channel or passage, *b*, which terminates at its rear end into an opening or slot, *b'*.

B is the coupling-hook which, with its shank or straight rod portion having axial movement in the passage *b*, is cast in one piece, which rod portion or shank is provided with a handle, *d*, keyed or otherwise suitably connected thereto at right angles to the length of said shank or rod portion. This lever or handle, which moves in and extends through the slot or opening *b* of the draw-head A, and normally rests in an outwardly and downwardly inclined position, serves as a weight by the gravity of which the coupling-hook is normally held at about an angle of ninety degrees to a horizontal plane in alignment with and slightly beyond the entrance of the draw-head, whereby as two draw-heads come together the hooks will have such relation that they will readily pass and interlock with each other, and thus effect the automatic coupling

of the cars. The lever or handle *d*, with its slot, also serves to retain in position the coupling-hook.

In order to render effective the coupling action or operation of the parts and to securely interlock the same, the beak of the hook is inclined inward toward and to its free end, while at the point of or junction of its beak with its shank or rod portion it is beveled to prevent the same from abruptly striking the draw-head in its recess or concavity, allowing it to readily ride thereinto. The handle *d* has an aperture in its outer end for the convenient attachment thereto of a cord or chain, or other suitable means for its operation from an elevated point—as, for instance, upon the top of a house or stock car—while it is capable of ready operation without compelling going between the cars by the application of the hand directly to said handle. As the hooks of two draw-heads come together it will be observed that the handles *d* will be thrown up, and as soon as the hooks interlock or couple the weight or gravity of the elevated lever or handle will of course have the effect to cause them to fall or automatically return to their former lowered position and thus effect the coupling operation.

Having thus fully described my invention, what I claim, and desire to secure by Letters Patent, is—

1. In a car-coupling, the combination, with the draw-head having a conical recess or concavity and an opening or slot, of the coupling-hook having its beak inclined inward and beveled at the point of junction of the beak and the shank or rod portion and provided with a handle, substantially as shown and described.

2. In a car-coupling, the coupling-hook having its beak inclined inwardly and its shank or rod portion beveled, and the draw-head having a conical recess or concavity adapted to receive said coupling-hook, substantially as set forth.

In testimony whereof I affix my signature in presence of two witnesses.

JOHN A. MURRAY.
